UNITED STATES PATENT OFFICE.

CHRISTIAN N. SMITH, OF ELGIN, ILLINOIS, ASSIGNEE OF ONE-HALF TO WILLIAM P. TOPPING, OF ELGIN, ILLINOIS; ALICE MINNIE SMITH AND LILY IRENE SMITH, EXECUTRICES OF SAID CHRISTIAN N. SMITH, DECEASED.

MACHINE FOR BENDING METALLIC PRINTING PLATES SUCH AS STEREO TYPE AND ELECTRO TYPE PLATES.

Application filed April 24, 1922. Serial No. 556,310.

This invention relates to that class of machines adapted to be used for bending metallic printing plates, such as stereotype or electrotype plates, into suitably curved form 5 for use upon printing presses requiring curved or circular printing plates either in the form of electrotype or stereotype plates.

The principal object of this invention is to provide a simple, economical and efficient 10 machine for bending metallic printing plates, such as stereotype or electrotype plates.

Other and further objects of the invention will appear from the following description 15 and claims, and from an inspection of the accompanying drawings, which are made a part of this specification.

The invention consists in the features, 20 combinations, details of construction and arrangement of parts, and in the method or process of heating, preparing and bending metallic printing plates, such as stereotype and electrotype plates, herein described and claimed.

Subject matter of invention herein described and not claimed will be found described and claimed in an application Serial 25 No. 63,114 filed by me and in my name in the United States Patent Office on October 17, 1925, for an improvement in processes for heating and bending metallic plates such as stereotype and electrotype plates, to which attention is hereby directed.

In the accompanying drawings—

Figure 1 is a plan view of a printing-plate bending machine constructed in accordance with my invention, and adapted to be used in the practice of my improved method or process of bending printing plates, 35 such as stereotype or electrotype plates;

Fig. 2 is a view in central vertical section of the machine shown in Fig. 1, taken on line 2-2 of said figure, looking in the direction indicated by the arrows, and showing the 45 adjustable roller or cylinder, and the mechanism for adjusting the same, in front elevation;

Fig. 3 is a sectional plan view taken on line 3-3 of Fig. 2 looking down, and showing 50 the top of the stationary table, and the rotary table or turn table, and the means for supporting the bending rolls or cylinders,

and means for holding the lower extremities of said rolls in operative position;

Fig. 4 is a view in perspective of a heating 55 and bending roll or cylinder constructed in accordance with my invention and adapted to be used in the practice of my improved process of heating and bending metallic printing plates, such as stereotype and electrotype plates, and showing a metallic printing plate in position to be bent, and outer flexible bending sheets attached to the periphery of the cylinder, and strips and sheets of compressible material or temporary 60 matrix-forming material interposed between the metallic plate to be bent and the outer bending sheets;

Fig. 5 is an enlarged detail end view, 65 looking downward, of a portion of the bending roll, a printing plate in process of being heated and bent, and the outer bending sheets and intermediate matrix-forming compressible plastic material or sheets, shown in Fig. 4;

Fig. 6 is an enlarged detail view in perspective of a metallic printing plate, provided with a layer of compressible material such as paper pulp in a moist plastic condition laid upon the printing face and filling 80 the spaces between the lines of type and between the printing faces or actual printing surfaces of the plate, and having a plurality of flexible backing sheets, including an outer metallic backing sheet laid upon or in parallel relation to the plastic layer or filler, and all adapted to be bent simultaneously while in operative engagement and in a suitably heated condition to dry the intermediate 85 layer of plastic material and cause it to set and form a temporary matrix while in contact with the printing surface of the metallic printing plate, in accordance with my invention.

In constructing a machine for heating and bending metallic printing plates, which may be either stereotype plates or electrotype plates, in accordance with my invention, I provide a main frame 1, adapted to form a 95 table or bed 2, and having supporting legs 3, adapted to support the table or bed in convenient position for use.

Upright frame portions 4, which may be located at opposite ends of the table or bed

2, are fixed to the main frame and extend upward or in perpendicular relation to the surface of the table or bed 2. Supported upon the upper or outer ends of these frame 5 arms or columns 4 is a top frame member 5, which extends from end to end of the main frame and table and in parallel relation to the top surface of the table. The top frame or outer frame member 5, is thus 10 supported in fixed position up and spaced apart in relation to the top surface of the table, and is adapted to form a strong and rigid support for the adjacent or upper ends of the heating and bending rolls, hereinafter 15 described.

A hollow main heating and bending roll 6 is provided, having an upper journal portion or axle 7 and a hollow hub or lower annular flange 8 projecting from the upper and lower ends of the roll, respectively. This main heating and bending roll is formed of metal and being hollow forms an inner upright heating chamber 9, having a central bottom axial opening 10, formed by 25 the hollow hub or sleeve 8, and having upper outlet openings 11 in the upper wall 12, and in position to permit the escape of the heating fluid or gases and products of combustion.

30 Mounted on the inside of the heating and combustion chamber 9, formed by the hollow roll 6, is a series of upwardly and outwardly inclined baffle plates 13, which are supported in superposed relation by a suitable supporting means which may be in the form of an upright axial depending rod 14, the upper end of which is secured to and depends from the axial center of the upper end of the roll 6, as shown in Fig. 2. A supporting plate 15, fixed to the upper end of the rod 14, and having its top face in contact with the inner face of the end wall 12, is rigidly secured to said end wall by means of bolts or rivets 16, or other suitable securing means. It is obvious, however, that the baffle plates may be supported in operative position on the inside of the heating chamber 9, by any ordinary and well known form of supporting 45 means adapted to support the baffle plates in properly spaced-apart superposed relation so as to provide spaces 17, between the outer peripheries or edges of the baffle plates and the inner peripheral wall 18, of 50 the hollow heating and bending roll.

In order to provide suitable, simple and efficient means for rotatively supporting and heating successively and in any desired order, any desired number of interchangeable 60 hollow heating and bending rolls 6, of different sizes or dimensions, so as to enable metallic printing plates of different sizes and dimensions to be heated and bent to different degrees of curvature, or so as to 65 form the arcs of circles of different diam-

eters, or adapted to be used upon printing presses, having rotative cylinders of different sizes or diameters, I provide a rotative platform or turntable 19, which is rotatively mounted upon the main frame 1, and, by preference, has its upper surface in substantially the same horizontal plane with the top surface of the stationary table 2. (See Fig. 2.)

This turntable is, by preference, rotatively mounted in a circular opening or recess 20, in the main frame or stationary table 2, and has a hollow downwardly extending vertical axle 21, fixed to the turntable and journaled in a suitable bearing 22, in a supporting bracket 23, which is rigidly secured to the main frame 1, by means of bolts 24, or other suitable securing means, and adapted to form a strong and rigid stationary support for the turntable, and for the means for heating and operating the turntable and any heating and bending roll which may be mounted upon the turntable and used in connection therewith, in accordance with my invention.

90 Fixed to and extending downward from the axial center of the turntable 19, and forming a part thereof, is a hollow casing, shell or body portion 25, which forms a central combustion chamber 26, in which is mounted a gas burner 27, which may be of any desired, ordinary and well known or suitable form. The burner 27 is, of course, provided with a suitable supply pipe or 95 passage 28, which is adapted to communicate with a suitable combustible fluid supply, which may be of any desired, ordinary and well known form. The combustion chamber 26 has an inlet opening 29, which is, by preference, formed in the axle 21 and adapted to admit air or other fluid to the chamber 26, and heating chamber 9, during the rotation of the turntable and any heating and bending roll operatively supported thereby. The turntable 19 is provided with an axial opening 30, adapted to removably admit the hollow hub or depending flange 8, so as to 100 form an outlet or connecting passage leading from the combustion chamber 26 into the lower extremity of the heating chamber 9, of any heating and bending roll 6 which may be mounted upon the turntable.

105 The depending bottom end flange or hub 8 of each of the interchangeable heating rolls 6, is provided with recesses 31 in the periphery of the hub and adapted to admit and detachably engage inwardly projecting corresponding lugs 32, on the inner edge or perimeter of the turntable. And the upper journal or axle 7 of each removable heating and bending roll 6, is removably mounted in a suitable bearing in the upper or outer frame member 5. A journal box or bearing block 33, having projecting side flanges or 110

120

125

130

lugs 34, is removably mounted in a suitable opening 35, in the upper frame member 5, and provided with a central opening 36, through which the shaft or journal extends. The bearing block 33 is removably held in place by means of a removable fastening or clamping member 37, which extends across the opening 35, and is detachably secured to the frame member 5, by means of headed 10 screws or bolts 38, or other suitable securing means. A sufficient space 39 is provided between the top frame member 5 and the adjacent end of the heating and bending roll 6, to permit the latter to be conveniently 15 raised out of engagement with the turntable 19. And an eye or loop 40, or similar lifting means, is provided and secured to or mounted upon the upper extremity of the axle 7, and adapted to admit a cable or lifting hook, 20 or other suitable lifting means for raising the heating and bending roll 6, out of operative engagement with the turntable, and enabling the removal of any heating and 25 bending roll to be accomplished with facility, although such roll may be in a heated condition.

A driving gear or worm wheel 41, is fixed to the hollow depending axle 21 of the turntable 19, and a driving worm or screw 42 is rotatively mounted in a suitable bearing 43, in the bracket 23, or other suitable support, and in toothed operative engagement with the worm wheel 41. The worm 42 is, 35 of course, fixed to a suitable driving shaft 44, which is adapted to be operatively connected with a suitable driving gear or other source of power, such as a motor or engine, which may be of any desired, ordinary or 40 well known form.

A bottom bracket arm 45, forms a bearing 46, for the lower extremity of the hollow vertical axle 21 of the turntable. And anti-friction idler rollers 47, are rotatively mounted in pockets or recesses in the stationary table 2 or bed of the main frame, and in engagement with the periphery 48, of the turntable 19.

Mounted adjacent to, and with its cylindrical periphery in parallel relation to the peripheral surface of the heating and bending roll 6, is a supplementary or auxiliary bending roll 49. This auxiliary bending roll 49 has its vertical axis in parallel relation 50 to the axis of the heating and bending roll 6, and is adjustably supported in the main frame, so as to enable the said roll 49 to be 55 adjusted toward and securely held in operative position with respect to the axis of a heating and bending roll 6, in case such heating and bending roll is of relatively small diameter, and permit the roll 49 to be moved away from the axis of rotation of the turntable 19, and any heating and bending 60 roll mounted on such turntable, when such

heating and bending roll is of relatively large diameter as compared with other interchangeable heating and bending rolls.

In order to provide simple and efficient means for adjusting and rotatively supporting the auxiliary bending roll 49, in any desired predetermined adjusted operative position, the roll is provided with an upper journal or axle portion 50, and a lower journal or axle 51. The upper journal 50 is rotatively mounted in adjustable relation to the upper frame member 5, and the lower journal 51, extends through an opening 52, in the stationary table 2, and is adjustable with respect to the latter.

An upper adjustable bearing block 53, is slidably mounted in an elongated opening 54, in the top frame 5, and is supported upon and between parallel guiding ways 55, on opposite sides of said opening. The bearing block 53 slidably engages the parallel guiding ways or side walls 55 of the elongated metallic backing sheet secured to and adapted to hold the bearing block in operative position with respect to the slotted top frame 5, in which the block is mounted.

A similar bottom sliding journal block 57, is slidably mounted in the elongated opening 52 in the table 2, and has a central opening 58, in which the bottom journal 51 is rotatively mounted. The bottom bearing block 57 is slidably mounted between and supported by its flanges 56 on parallel guiding ways or flanges 59, on opposite sides of the elongated opening 52, which is open or sufficiently large at one extremity of said opening to admit the block when the parts are assembled.

Suitable adjusting means is provided and operatively connected with the upper and lower sliding journal bearing blocks 53 and 57, and may be of any desired and well known or suitable form. The adjusting means here shown, however, and which has been found in practice to be simple and economical in construction and efficient in operation, is constructed as follows:

A non-rotative threaded screw 60, is secured at one end to the bearing block 53, by means of a securing pin 61, or other suitable means for holding the screw in fixed relation to the bearing block. A similar threaded adjusting screw 62, is mounted in a suitable support 63 in the main frame and below the table 2, and lower extremity of the bending roll 49, and is connected at one end with the sliding block 57, by means of a pin 64 or other suitable means for securing said screw in fixed relation to said lower sliding journal bearing block.

The non-rotative adjusting screws 60 and 62, are in parallel relation to each other, and in perpendicular relation to and in the same vertical plane with the axes of the bending rolls 6 and 49, and adapted to enable the

roll 49 to be moved toward and from the adjacent bending roll 6, and to be constantly in position to extend over the outer peripheral portion of the turn-table 19. A bevel gear wheel 65, having a screw threaded axial opening therein, is mounted upon and in screw-threaded engagement with the non-rotative screw 60; and a similar bevel gear 66, having a screw-threaded axial opening therethrough, is mounted on and in screw-threaded engagement with the lower non-rotative screw 62. An operating shaft 67 is rotatively mounted in suitable bearings 68, in the frame, and between and in perpendicular relation to the axes of the screws 60 and 62. And a bevel gear wheel 69 is mounted upon and in fixed relation to the upper extremity of said shaft 67, and in toothed engagement with the bevel gear wheel 65, already described. A similar bevel gear wheel 70 is fixed to the lower extremity of the shaft 67, and is in toothed engagement with the bevel gear wheel 66, on the lower adjusting screw 62. A hand wheel or other suitable operating means 71 is mounted upon, or operatively connected with, the operating shaft 67. The bevel gear wheels 65 and 66 have their hubs in engagement with the adjacent outer surfaces of the machine frame and are mounted between the machine frame and the corresponding bevel gears 69 and 70 on the shaft 67. From the foregoing it will be readily understood that the gear wheels 65 and 66 are rotatively mounted upon the respective adjusting screws 60 and 62, and are adapted to cause said adjusting screws to move in opposite directions successively, according to the direction of rotation of the operating shaft 67 and gears 65, 66, 69 and 70.

The hollow heating and bending roll 6 is provided with a peripheral printing-plate engaging bar or strip 72, which extends longitudinally of the roll, and by preference, from end to end thereof and in parallel relation to the axial center of the roll. The plate holding strip or bar 72 is provided with a side flange 73, which projects over a corresponding inner longitudinal marginal notch or recess 74, which is adapted to receive and removably hold in position a corresponding margin or edge 75 of a metallic printing-plate 76, during the operation of heating and bending the plate, which may be either a stereotype plate or an electrotype plate. The marginal flange 73 of the bar 72 is adapted to project over the adjacent marginal portion of the metallic printing-plate 76 to be heated and bent, and to removably hold said margin of the plate between said flange and the adjacent peripheral surface of the heating and bending roll 6. An outer flexible backing sheet or plate 77, which is, by preference, made of flexible sheet metal, extends over the outside of the

printing-plate holding-bar 72, and from end to end of said bar, and has its forward edge 78 secured to the peripheral surface of the heating and bending roll 6, in advance of said bar 72, by means of a metallic securing strip 79 and rivets 80, or other suitable securing means. The flexible metallic outer backing plate 77 is of sufficient length to completely or almost completely encircle the bending roll 6, on which it is mounted; and a similar inner or intermediate flexible sheet 81, is mounted in engagement with the inner face of the outer plate 77, and is adapted to be held by the latter in operative engagement with an adjacent intermediate strip, 80 layer or sheet 82, of softer material than metal. The plate 82 may be formed of suitable flexible material, such for example, as hard rubber. And in preparing the metallic printing plate for heating and bending, in accordance with my improved process and invention, a sheet of compressible material, such, for example, as paper pulp 83, or similar compressible fibrous material, is interposed between the sheet 82 and the metallic printing-plate 76 and in contact with the printing side of the metallic printing plate, while the compressible material forming the sheet or layer 83 is in a moist plastic condition. And strips or fragments 84, which may be of paper pulp in a moistened plastic condition, or in the form of a coating or layer of any suitable plastic material, may, if desired, be applied to the printing surface of a metallic printing-plate, so as to fill the spaces between the lines of type, and between the actual printing faces of the type, and other depressions or indentations in the printing side or face of the metallic printing-plate. In practice, the strips or fragments 84 of pulp or other plastic material or coating are not required between the moist sheet of paper pulp 83 and the printing side of the printing plate and may be dispensed with. And I, by preference, employ the moist or saturated plastic sheet of paper pulp or moist compressible temporary-matrix-forming material, sheet or pad 83 in actual contact with the printing side of the metallic printing plate and without any strips or fragments or other element 84 between the sheet of moist compressible material or paper pulp 83 and the surface of the printing plate. (See Figs. 1 and 6.) The layer or filler of compressible material thus applied to the printing surface of a metallic plate to be heated and bent, is adapted to be pressed into tight engagement with the printing surface of the printing-plate while such filler is in a plastic condition, and to be dried and heated, and caused to set either before being bent with the printing-plate, or progressively during the operation of heating and bending the printing-plate, and the filler or temporary

matrix, and the flexible backing sheets, or plates, in accordance with my improved process and invention.

From the foregoing description, it will be readily understood and appreciated by those skilled in the art that any desired number of interchangeable hollow heating and bending rolls of different diameters, for bending metallic printing plates for use upon printing presses having cylinders of different diameters, may be used interchangeably in any desired order, each being removably mounted, and by preference, with its axis in a vertical position, upon and detachably connected with and in fixed relation to the rotary support or turntable, and in position to form a heating chamber within such interchangeable removable heating and bending roll, and communicating with the combustion chamber formed in, upon, or under the turntable or below the surface thereof, and adapted to be heated by a gas burner, or other suitable heating means.

I have found in practice, however, that it is highly desirable to provide means for heating the metallic printing plate, and its plastic filler or layer, sheet or pad 83 of moist or plastic, or moisture-containing or liquid-containing material, such, for example, as moist or moisture-containing or liquid-containing paper, or saturated or partially saturated pulp or similar material forming a temporary matrix, to a very high temperature, so as to bend the metallic printing plate evenly and uniformly and at the same time cause the plastic filler or temporary matrix to be progressively dried, bent and caused to set in its curved form thus causing the moisture in the sheet or pad of moist compressible fibrous material or paper pulp 83 to expand in the form of steam and escape or evaporate, thus acting to dampen or moisten and prevent overheating of the metallic printing plate simultaneously with the operation of progressively heating and bending the metallic printing plate to be operated upon.

The temporary matrix or filler thus caused to dry and set progressively, fills the recesses and depressions in the printing face of the printing plate which is thus heated and bent uniformly throughout its entire area.

In bending metallic printing plates, which may be either stereotype or electrotype plates, by the use of my improved bending machine or apparatus. I proceed in practice, by preference, as follows: One or more layers or sheets 83 of moist plastic or compressible filler material, such for instance, as paper pulp, are laid upon and in contact with the printing side or face of the printing plate, while said sheet or sheets 83 are in a moist or plastic condition; and a backing sheet or layer 82 of flexible material,

such for example, as hard rubber, is interposed between the plastic or compressible layer 83 and an outer sheet or sheets of flexible backing material 77, 81, which may be of sheet metal.

The metallic printing plate, with its layer or layers of plastic material on the printing surface thereof, and with the backing sheet or sheets laid in contact with and covering the outer surface of the filler sheet or layer 75 of plastic or moist material, is then heated progressively from margin to margin thereof, to the desired suitable predetermined temperature to render the metallic printing plate sufficiently pliable and flexible while 80 hot to be bent into the desired shape, although said printing plate is sufficiently hard to retain its shape into which it is bent when the operation of heating and bending has been completed and the plate allowed to 85 cool and set while firmly held in position upon the periphery of the heating and bending roll and between the surface of said roll and the flexible backing sheets during and immediately following the operation of 90 causing the printing plate to pass between the opposed peripheral surfaces of a plurality or set of bending rolls.

I prefer in most instances that the filler coating or layer or sheet 83 of moist paper 95 pulp or similar compressible plastic or fibrous material should be in a moist or plastic condition while passing between the rolls in the operation of being heated and bent, and that the moist and plastic or compressible filler material or sheet 83 should be heated and dried or partially dried while in contact with the metallic printing plate and while being compressed against and bent with the printing plate and acting to fill all 100 of the depressions and interstices in the printing surface of the same.

A temporary matrix is thus formed or obtained by heating and drying and causing the plastic filler material such, for example, as the moist sheet of paper pulp 83 to dry or partially dry while in contact with the printing surface of the printing plate and during the operation of heating and bending the latter.

Suitable heating and bending rolls having been provided, such, for instance, as the rolls above described, which have their axes in parallel relation, and comprise a hollow heating and bending roll forming a heating 120 chamber and having its axis in parallel relation to an adjustable bending roll which may or may not be heated, as desired, I also provide suitable means for supporting said rolls in operative position, and means for 125 heating and operating one or both of said rolls in an efficient manner, as above described, including a rotary support or turntable for supporting and rotating one of said rolls, and extending laterally beyond 130

and beneath the lower end margin or peripheral edge of such roll so as to support and guide the bottom edge of a printing plate and its filler and backing sheets. Said metallic printing plate,—which may be either a stereotype or an electrotype plate, with its filler sheet or layer of plastic material and its backing sheets already described,—is placed in position to pass between said rolls, with the lower edge of the printing plate resting on the turntable and supported and guided thereby and with the front upright edge of the printing plate and filler clamped in upright position between the heated hollow roll and the flexible backing sheets and in engagement with the plate-holding bar already described. And the metallic printing plate, with its filler, pad or sheet of moist compressible pulp or fibrous material, such, for example, as the sheet or pad 83 and backing sheets, are thus caused to pass between the bending rolls, and is heated to a very high temperature and thereby rendered pliable, and bent to the desired degree of curvature, and at the same time the plastic filler is pressed into and caused to fill all of the depressions in the printing side of the printing plate, and progressively dried and hardened in its curved form and during the operation of heating and bending the plate, as already described.

The uniformly curved metallic printing plate, with its filler in contact with its printing surface, is then removed from the bending rolls, and the filler or temporary matrix is removed from the surface of the printing plate, leaving the latter uniformly curved throughout its entire area, and ready for use in printing.

From the foregoing description it will be readily understood that the above described machine is adapted for bending copper printing plates, zinc plates, or aluminum plates, or printing plates of any suitable material.

My improved printing-plate bending machine constructed in accordance with my invention and having a moist layer or sheet, or a moisture-containing or liquid-containing sheet or sheets of absorbent material, such as saturated or partially saturated or moistened paper pulp, or similar material adapted to engage the printing side of the printing plate, can be successfully used for bending some printing plates while cold—for example, electrotype plates. I prefer, however, to heat the plates, and to bend them while hot, particularly stereotype plates. And I have found in practice that more satisfactory results are accomplished by heating and moistening the plates to be bent.

I claim:

1. In a machine of the class described, the combination of a heating and bending roll rotatively mounted, means for heating said

roll, a second roll rotatively mounted adjacent to the first-mentioned heating and bending roll and adapted to admit a metallic printing plate between said rolls, to be heated and bent, a moisture-containing element adapted to pass between the rolls in engagement with the face of the printing plate and means for rotating said first mentioned heating and bending roll.

2. In a machine of the class described, the combination of a hollow heating and bending roll rotatively mounted and forming a heating chamber, means for heating said heating chamber, a second bending roll rotatively mounted adjacent to and adapted to co-act with said first-mentioned heating and bending roll in the operation of heating and bending a metallic printing plate, a moisture-containing flexible sheet adapted to pass between said rolls in engagement with the printing side of such metallic printing plate, for filling the interstices and depressions therein and moistening said printing plate to prevent the same from becoming overheated, and means for rotating one of said rolls.

3. In a machine of the class described, the combination of a heating and bending roll rotatively mounted, means for heating said roll, a second bending roll mounted in parallel relation to and adapted to co-act with said first-mentioned heating and bending roll in the operation of heating and bending a metallic printing plate, a flexible backing sheet adapted to pass between said last-mentioned roll and said printing plate, a moisture-containing sheet of flexible compressible material interposed between said flexible backing sheet and said printing plate and adapted to engage the printing side of the latter for moistening said printing plate and preventing the same from becoming overheated during the operation of heating and bending said plate, and means for rotating said first-mentioned heating and bending roll.

4. In a machine of the class described, the combination of a hollow heating and bending roll forming a heating chamber, means for heating said heating chamber, a second bending roll rotatively mounted adjacent to and having its axis in parallel relation to the axis of said first-mentioned heating roll and adapted to co-act with said hollow heating and bending roll in the operation of heating and bending a metallic printing plate, a flexible metallic backing sheet adapted to extend around a portion of the periphery of said first-mentioned heating and bending roll, a flexible sheet of moisture-containing compressible material interposed between said flexible metallic backing sheet and the metallic printing plate and adapted to engage the printing side of said printing plate, for filling the interstices and

depressions in said printing plate and moistening said printing plate, to prevent the same from becoming overheated during the operation of heating and bending said plate, and means for rotating said first-mentioned hollow heating and bending roll.

5. In a machine of the class described, the combination of a hollow heating and bending roll rotatively mounted and forming a heating chamber having inlet and outlet openings, heating means comprising a gas burner adapted to heat said heating chamber, a second bending roll mounted in parallel relation to said hollow heating and bending roll and adapted to admit a metallic printing plate between said rolls, to be heated and bent, flexible plate-engaging means comprising a moisture-containing flexible sheet adapted to pass between said rolls in engagement with the printing side of such metallic printing plate, for filling the interstices and depressions therein and moistening said printing plate to prevent the same from becoming overheated, and means for rotating one of said rolls.

6. In a machine of the class described, the combination of a hollow heating and bending roll rotatively mounted and forming a heating chamber, said roll having a vertical axis, heating means comprising a gas burner adapted to heat said heating chamber, a second bending roll mounted in parallel relation to said hollow heating and bending roll, a flexible backing sheet adapted to extend around a portion of the periphery of said hollow heating and bending roll, for holding a metallic printing plate in position upon and in contact with the periphery of said roll, to be heated and bent, moistening means interposed between said flexible backing sheet and said printing plate and adapted to engage the printing side of the latter, for moistening said printing plate, to prevent the same from becoming overheated during the operation of heating and bending the plate, and means for rotating said first-mentioned heating and bending roll.

7. In a machine of the class described, the combination of a hollow heating and bending roll forming a heating chamber having inlet and outlet openings, said roll having a vertical axis of rotation, a journal on the upper end of said roll, a journal bearing for said journal, turntable adapted to form a rotative support for said hollow heating and bending roll, a support for said turntable having a fluid passage leading through said turntable and communicating with the heating chamber in said roll, a support for said burner, means for connecting said burner with a source of fuel supply, a second bending roll mounted adjacent to and having its axis in parallel relation to the axis of the first mentioned hollow heating and bending

roll, and means for rotating said turntable and hollow heating and bending roll.

8. In a machine of the class described, the combination of a hollow heating and bending roll forming a heating chamber having inlet and outlet openings, said roll having a vertical axis of rotation, a journal on the upper end of said roll, a journal bearing for said journal, a turntable adapted to form a rotative support for said hollow heating and bending roll, said turntable having an opening beneath the said roll and adapted to communicate with the interior of the latter, a support for said turntable, means for securing said hollow heating and bending roll in fixed relation to said turntable, and in position to admit heated fluid passing through said opening in the turntable to the interior of said hollow roll, means for introducing heated fluid through said opening in the turntable and into the interior of said hollow roll, for heating the latter, and means for rotating said turntable and said roll.

9. In a machine of the class described, the combination of a hollow heating and bending roll forming a heating chamber having inlet and outlet openings, and having a vertical axis of rotation, a journal on the upper end of said roll, a journal bearing for said journal, a turntable adapted to rotatively support said hollow heating and bending roll, means for detachably securing said hollow heating and bending roll in fixed relation to said turntable, a support for said turntable, means for introducing heated fluid into the interior of said hollow heating and bending roll, a second bending roll mounted adjacent to and having its axis in parallel adjustable relation to the axis of said first-mentioned hollow heating and bending roll, and means for rotating said rolls.

10. In a machine of the class described, the combination of a hollow heating and bending roll forming a heating chamber having inlet and outlet openings and having a vertical axis of rotation, baffle plates in said chamber, a journal on the upper end of said roll, a journal bearing for said journal, a turntable adapted to rotatively support said hollow heating and bending roll, a support for said turntable, means for detachably securing said hollow heating and bending roll in operative position upon said turntable, means for introducing heated gas into the interior of said hollow heating and bending roll during the rotation of the latter, a second rotative bending roll mounted adjacent to said first-mentioned hollow heating and bending roll and adapted to admit a metallic printing plate, flexible backing plate and intermediate filler sheet material between the peripheries of said rolls, to be heated and bent, and means for rotating said rolls.

11. In a machine of the class described,

the combination of a hollow heating and bending roll forming a heating chamber having inlet and outlet openings, said roll having a vertical axis of rotation, a journal 5 on the upper end of said roll, a journal bearing for said journal, a turntable rotatively mounted and adapted to rotatively support said hollow heating and bending roll, said turntable having a peripheral marginal portion 10 projecting beyond the periphery of said roll at the lower end of the latter and adapted to support and guide a metallic printing plate to be heated and bent, means for securing said hollow heating and bending roll 15 in operative position upon said turntable, means for introducing heated fluid into the interior of said hollow heating and bending roll during the rotation of the same, a second rotative bending roll mounted adjacent 20 to said first-mentioned hollow heating and bending roll, and means for rotating the turntable and said hollow heating and bending roll.

12. In a machine of the class described, 25 the combination of a hollow heating and bending roll forming a heating chamber having inlet and outlet openings, said roll having an upwardly and downwardly extending axis, means for rotatively supporting the upper end of said roll in operative position, a turntable rotatively mounted and adapted to rotatively support said hollow heating and bending roll in operative position, said turntable having a peripheral 30 portion projecting beyond the peripheral margin of the lower end of said heating and bending roll, means for securing said roll in operative position upon said turntable, means for introducing heated 35 fluid into the interior of said hollow roll, anti-friction rollers mounted in engagement 40 with the peripheral margin of said turntable, a second rotative bending roll mounted adjacent to said first-mentioned hollow heating and bending roll and adapted to 45 permit the passage of a metallic printing plate between the peripheries of said rolls, and adapted to tend to press the hollow heating and bending roll toward said anti-friction rollers, and means for rotating said 50 turntable and said hollow heating and bending roll.

13. In a machine for heating and bending metallic printing plates, the combination of 55 a hollow heating and bending roll, rotative driving mechanism, for rotating said roll, means for rotatively supporting said driving mechanism, means for detachably connecting the hollow heating and bending roll 60 with said rotative driving mechanism and adapted to permit the removal of said roll from its support without removing said driving means from its support, and means for heating said roll.

14. In a machine for heating and bending

metallic printing plates, the combination of a hollow heating and bending roll rotatively mounted, driving means comprising shaft and gear mechanism for rotating said heating and bending roll, means for rotatively supporting said driving shaft and gear mechanism, and means for detachably connecting said hollow heating and bending roll in operative engagement with the driving means and adapted to permit the removal of said roll from its support independently of and without removing said driving means from its support.

15. In a machine for heating and bending metallic printing plates, the combination of 80 a hollow heating and bending roll rotatively mounted, rotative driving mechanism for rotating said roll, means for rotatably supporting said driving mechanism, means for detachably connecting said hollow heating and bending roll with said driving mechanism and adapted to permit the removal of said roll from its support independently of and without removing said driving mechanism from its support, and means for heating 90 said roll.

16. In a device for heating and bending metallic printing plates, the combination of a hollow heating and bending roll forming a heating chamber and having a peripheral 95 portion adapted to operatively engage a metallic printing plate to be heated and bent, means for heating said roll, a flexible metallic backing sheet secured to and adapted to extend around a portion of the periphery 100 of said roll and outside of the metallic printing plates to be heated and bent, a moisture-containing flexible sheet of fibrous material interposed between said flexible metallic backing sheet and the metallic printing 105 plate and in contact with the printing side of said printing plate, for filling the interstices and depressions in said plate and moistening said plate, to prevent the same 110 from becoming overheated during the operation of heating and bending the plate, a second roll adapted to operatively engage said flexible metallic backing sheet, and means for rotating the hollow heating and 115 bending roll, to simultaneously heat and bend the moistened metallic printing plate.

17. In a machine for heating and bending metallic printing plates, the combination of a hollow heating and bending roll, rotative supporting and driving mechanism comprising a turntable mounted in suitable bearings and in supporting engagement with said roll, means for operatively connecting said roll with said supporting and driving mechanism, and means for heating the roll.

18. In a machine for heating and bending metallic printing plates, the combination of a hollow heating and bending roll, rotative supporting and driving mechanism mounted in suitable bearings and in supporting 130

engagement with said roll, means for operatively connecting said roll with said supporting and driving mechanism, a burner for heating the roll, and means for supplying fuel to said burner.

19. In a device for bending metallic printing plates, a layer of moisture-containing material adapted to engage the printing side of a printing plate, and means for forcing said material into engagement with and into the interstices and depressions in the printing side of such printing plate, and for simultaneously bending the layer of moisture-containing material and the engaged metallic printing plate together.

20. In a device for heating and bending metallic printing plates, the combination of a sheet of moisture-containing material adapted to engage the printing side of a printing plate, means for heating said printing plate, and means for forcing such moisture-containing material into engagement with and into the interstices and depressions in the printing side of such printing plate, and for simultaneously bending the engaged moisture-containing material and the metallic printing plate together.

21. In a device for heating and bending metallic printing plates, the combination of a temporary-matrix-forming moisture-containing element comprising compressible sheet material adapted to engage and fill the interstices and depressions in the printing side of a printing plate, and means for forcing said matrix-forming sheet material into engagement with and into the interstices and depressions in the printing side of such printing plate and simultaneously heating and bending the engaged matrix-forming material and metallic printing plate together.

22. In a device for heating and bending metallic printing plates, the combination of a temporary-matrix-forming moisture-containing element comprising compressible material adapted to engage and fill the interstices and depressions in the printing side of a metallic printing plate, a flexible backing sheet mounted on the opposite side of the matrix-forming material from the printing plate to be operated on, and means adapted to operatively engage said flexible backing sheet and metallic printing plate respectively, and acting to force the matrix-forming material into engagement with and into the interstices and depressions in the metallic printing plate and simultaneously bending the engaged matrix-forming material and metallic printing plate together.

23. In a device for heating and bending metallic printing plates, the combination of a temporary-matrix-forming moisture-con-

taining member comprising compressible sheet material adapted to engage and fill the interstices and depressions in the printing side of a metallic printing plate, means for forcing said matrix-forming sheet material into engagement with and into the interstices and depressions in the printing side of such printing plate and simultaneously bending the engaged matrix-forming material and metallic printing plate together.

24. In a device for heating and bending metallic printing plates, the combination of a temporary-matrix-forming member comprising plastic compressible sheet material adapted to engage and fill the interstices and depressions in the printing side of a metallic printing plate, a flexible metallic backing sheet mounted on the opposite side of the matrix-forming material from the printing plate to be operated on, intermediate flexible sheet material interposed between said metallic backing sheet and the matrix-forming sheet material, means for heating the engaged matrix-forming material and metallic printing plate, and means adapted to operatively engage said flexible backing sheet and metallic printing plate respectively and acting to compress and force the matrix-forming material into contact with and into the interstices and depressions in the metallic printing plate and simultaneously bend the engaged matrix-forming material and metallic printing plate together.

25. In a machine for heating and bending metallic printing plates, the combination of a hollow heating and bending roll forming a heating chamber and having a peripheral portion adapted to operatively engage a printing plate to be heated and bent, a temporary-matrix-forming member comprising moisture-containing compressible sheet material adapted to engage and fill the interstices and depressions in the printing side of a metallic printing plate, a flexible metallic backing sheet mounted on the opposite side of the matrix-forming material from the printing plate to be operated on, means for heating the hollow heating and bending roll, a second roll adapted to engage said flexible metallic backing sheet, and means for rotating the hollow heating and bending roll, to simultaneously bend the matrix-forming material and the engaged heated metallic printing plate together.

Signed at Chicago, in the county of Cook and State of Illinois, this 12th day of April, 1922.

CHRISTIAN N. SMITH.
